UNITED STATES PATENT OFFICE.

WILLIAM L. EDGARTON, OF CHICAGO, ILLINOIS.

HAND STAMP.

Application filed November 22, 1923. Serial No. 676,256.

To all whom it may concern:

Be it known that I, WILLIAM L. EDGARTON, a citizen of the United States, and a resident of Chicago, in the county of Cook and State of Illinois, have invented certain new and useful Improvements in Hand Stamps, of which the following is a specification.

This invention relates to printing devices but more particularly to hand stamps of the pad-inker type and has for its primary object to provide an article of this class which is simple and economical in construction and advantageous in use.

Further objects of my invention are to provide an improved inking pad construction and means for attaching the same to the frame, and a novel and convenient method of marking the stamp to indicate at a glance the subject matter of the imprint.

Self-inking stamps generally have the inking pad merely cemented to the under face of the top plate of the support or frame and this has proven unsatisfactory as the pads frequently become detached or displaced. In my improved stamp, the pad is securely fastened to the frame and accidental displacement or detachment will not occur.

In this class of stamps the printing face is normally inverted and in contact with the inking pad. On account of the difficulty of observing the type, it is common practice for the user to operate the stamp upon a piece of paper to determine the nature of the imprint. I have rendered this unnecessary by securing a specimen of the imprint or other identifying matter on the upper face of the top plate of the frame where it may be readily seen at a glance.

The many other objects and advantages of my invention will be better understood by reference to the following specification when considered in connection with the accompanying drawing illustrating a selected embodiment thereof, in which:—

Fig. 1 is a side elevation, partially in section, of a hand stamp embodying the principles of my invention.

Fig. 2 is a vertical section on the line 2—2 of Fig. 1.

Fig. 3 is a horizontal section on the line 3—3 of Fig. 1, and

Fig. 4 is a detail perspective view of the inking pad construction.

Referring to the drawing, the stamp comprises the usual support or frame 5, stamp bearing member 6, handle 7, operating arms 8 connecting the handle with the member 6, guide post 9, and spring 10 normally retaining the member 6 in contact with the face of the inking pad 11. The lower extremities of the arms 8 are connected by a pin 12 passing through vertical slots or guide-ways 13 in the side members 14 of the frame and the stamp bearing member is pivotally mounted on this pin. This member 6 is inverted in the customary manner by tumbler blocks 15 secured upon the back thereof and co-acting with pins 16 and 17 projecting inwardly from the side members of the frame.

The inking pad comprises a sheet metal back 18, one or more layers 19 of ink-absorbing material, and a cover 20 of suitable fabric which secures the layers 19 to the back. This cover envelops the sides and under face of the ink-absorbing material and its edge portions 21 overlie the upper face of the back (Fig. 4). These edge portions may be cemented to the back. Small lugs 22 are formed on the metal back 18 and these are bent upwardly at substantially a right angle to the upper face of the back to permit them to be inserted through corresponding perforations 23 in the top plate of the frame 5. The pad is secured to the under face of this plate by thus inserting the lugs 22 and bending these lugs 22 to upright position.

In addition to attaching the inking pad to the frame in the manner described, the lugs 22 act to secure an identification card 24 upon the upper face of the top plate of the frame (Fig. 3). This card would prominently display an imprint of the stamp or carry such information regarding the same as would be necessary to provide complete identification. The card is provided with a central orifice 25 to permit the guide post 9 to pass therethrough and this orifice preferably is connected to one edge of the card by a slit, as 26, to enable the card to be installed or removed after the stamp is assembled.

In order to protect the card, I prefer to cover the face of the same with a sheet 27 of transparent material such as celluloid and this sheet is likewise held in place by the

lugs 22. This covering sheet is also provided with a central orifice, but there is no necessity for providing a slit as in the case of the card as the sheet is preferably installed when the stamp is assembled by the manufacturer and it is only necessary to raise the sheet slightly to permit a card to be inserted or removed.

It will be readily evident that my improved hand stamp is simple and economical in construction and advantageous in use. The pad is securely attached to the frame but may be quickly and easily detached for the purpose of renewal of the ink-absorbing material or cover. The identification card is conveniently placed and readily observed. It cannot become accidentally detached as could a mere pasted label and is easily changed.

I am aware that numerous changes may be made in the form and arrangement of parts without departing from the spirit of my invention, and I reserve the right to make all such as fairly fall within the scope of the following claims.

I claim as my invention:

1. In a hand stamp, the combination with a supporting frame, of an inking pad mounted on said frame and comprising a back plate, means on said plate for engaging said frame, and ink absorbing material carried by said plate.
2. In a hand stamp, the combination with a supporting frame including a top plate, of an inking pad on the under face of said plate comprising a metal back, attaching means on said back interlocking with said plate, and ink absorbing material secured to said back.
3. In a hand stamp, the combination with a supporting frame including a perforated top plate, of an inking pad on the under face of said plate comprising a metal back provided with attaching lugs inserted through the corresponding perforations in said plate and having their extremities bent over to interlock with said plate, and ink absorbing material secured upon the under face of said back.
4. In a hand stamp, the combination with a supporting frame including a perforated top plate, of an inking pad secured on the under face of said plate and comprising a

sheet metal back having attaching lugs formed on the edges thereof and bent to substantially a right angle to the upper face of the back, said lugs being inserted through the corresponding perforations in said plate and their projecting extremities bent over to form an interlocking connection with said plate, ink absorbing material on the underface of said back, and a fabric cover for said material extending over the face thereof and having its edge portions folded upon the upper face of said back. 55

5. In a hand stamp, a supporting frame including a top plate, and means for attaching an identification card upon the upper face of said plate comprising a plurality of members overlying the said face at an interval 70 therefrom and co-operating therewith.

6. In a hand stamp, a supporting frame including a top plate, and means for attaching an identification card upon the upper face of said plate including a plurality of 75 spaced lugs projecting from and overlying said face, the said lugs being adapted to engage the edges of said card.

7. In a hand stamp, a supporting frame including a top plate, an identification card 80 on the upper face of said plate, and a plurality of lugs projecting from and extending inwardly over said face for engaging the edges of said card at intervals to retain said card thereon. 85

8. In a hand stamp, the combination with a supporting frame including a perforated top plate, of an identification card and an inking pad respectively on the upper and the under faces of said plate, said inking 90 pad comprising a sheet metal back provided with upstanding lugs projecting through the corresponding perforations in said top plate and having their free extremities bent inwardly over the edges of said card to attach said pad and said card to said plate, and ink absorbing material on the under face of said back. 95

9. In a hand stamp of the class described, an inking pad comprising a metal back, attaching lugs formed on said back, ink absorbing material on one face of said back, and a fabric cover enveloping said back and said material to retain said material on said face. 100

WILLIAM L. EDGARTON.
